CLAIM

The ornamental design for a combined multi-purpose lantern with adjustable beam and adjustable stand therefor, substantially as shown and described.

DESCRIPTION

FIG. 1 is a front elevational view of the combined multi-purpose lantern with adjustable beam and adjustable stand therefor showing my new design;

FIG. 2 is a right side elevational view thereof, the left side being substantially in a mirror image;

FIG. 3 is a rear elevational view thereof;

FIG. 4 is a top plan view thereof;

FIG. 5 is a bottom plan view thereof;

FIG. 6 is a right side elevational view thereof with the adjustable stand in alternate positions.

FIG. 1

FIG. 3

FIG. 4

FIG. 5

FIG. 2

FIG. 6
